UNITED STATES PATENT OFFICE.

WILLIAM EDWARD FRANCIS GIBSON, OF NELSON, BRITISH COLUMBIA, CANADA.

AUTOMOBILE SIGNALING DEVICE.

Application filed February 17, 1925. Serial No. 9,751.

To all whom it may concern:

Be it known that I, WILLIAM EDWARD FRANCIS GIBSON, a citizen of the United States, and a resident of the town of Nelson, in the Province of British Columbia, Canada, have invented certain new and useful Improvements in Automobile Signaling Devices, of which the following is a specification.

10 My invention relates to improvements in automobile signaling devices and the object of my invention is to provide a simple and inexpensive device which can be readily and easily applied to an automobile of either the 15 open or closed type for manipulation by the driver to indicate the direction of travel of the car either straight ahead or to the right or left, as the case may be, or at intersections, bends, or turns in streets or highways, 20 thereby enabling observers to determine the course of the car and thus avoiding accident.

I attain this object by the construction illustrated in the accompanying drawings, in which—

25 Fig. 1 is an outside view of my device.

Fig. 2 is a longitudinal sectional view.

Fig. 3 is an outside view, illustrating the use of the signaling member.

30 Fig. 4 is a sectional plan view, the hand being extended.

Fig. 5 is an enlarged fragmentary view of the outer end of the device, the casing being removed.

35 Similar figures of reference indicate similar parts throughout the several views.

The device consists of a casing 1, of any suitable dimensions, the outer end of which is open, as at 2, while its inner end is closed as at 3 and provided with a tubular extension 4, threaded at its extremity as at 5 and having a nut 6 mounted on the threaded portion, as shown in Figs. 1 and 3.

40 Mounted in the bore of the extension 4 is a tubular rod 7 one end of which extends into the casing 1 and is split to provide divided ends 8 and 9 and a longitudinal slot 10 of suitable length and width, while its opposite end extends to a point within easy reach of the operator when the device is in place, as hereinafter described, and is provided with a longitudinal slot 11.

45 Normally housed within the casing and disposed horizontally therein is the signaling member, which in this case is shown in the form of a hand, indicated by the nu-

50 meral 12, which hand is constructed of thin sheet metal and has its inner end formed as two spaced discs 13 and 14 pivotally connected respectively to the divided ends 8 and 9 of the tubular rod 7 by pivots 15 and 16, and secured at its lower edge to the inside of one of the discs; in this case 13, is a thin metal strip 17 spaced at its upper edge slightly apart from the disc, to which strip is connected the outwardly bent end 18 of a rod 19 which extends longitudinally through the bore of the tubular rod 7, the opposite end 20 of this rod 19 being bent downwardly and passed freely through the slot 11 in the tube 7. The end 20 is eyed as at 21 so that it may be connected by a pin 22 to the lower end of a normally vertical handle 23 pivotally mounted on a pin 24 extending from side to side of the member 7 and preferably intermediate the length 55 of the slot 11, although another hole or holes, indicated by the numeral 25, may be provided to receive the pin 24 and enable adjustment of the position of the handle longitudinally of the slot to be effected, if 60 desired.

65 Fig. 2 indicates a pin secured transversely through the rod 7 positioned to act as a stop to limit the outward movement of the rod past the point necessary for exposing 70 the signal, while 28 and 29 indicate clamp portions adapted to secure the device to the side standard 30 of a windshield 31, of an open car, a fragmentary portion of these 75 two latter elements being shown in Figs. 1 and 2 for the purpose of illustration. For use with a closed car, the clamps are dispensed with, and the extension 4 is passed through the side of the car till the end 3 abuts against the outside of the car, the nut 6 being tightened up, after which the operating parts are assembled, and to ensure 80 steadiness of the casing and prevent its moving from a vertical position a steady pin 32 is provided on the end 3 which extends into the side of the car. The casing may have 85 spots painted on its front side to represent buttons, as if it were a coat sleeve, as indicated by the numeral 33 in Figs. 1 and 3.

90 The manner in which the device operates 95 will be readily seen. It is mounted so that the casing 1 projects outwardly and horizontally from the left hand side of the automobile with the handle 23 within easy reach of the driver, the signal hand 12 being nor-

2
mally out of sight and housed within the casing. When turning to the left the handle 23 is gripped and the tubular rod 7 and the hand 12 moved outwardly, the hand being 5 then exposed in a horizontal position and left in such position until the turn is made, when it is again drawn into the casing by moving the rod 7 in the opposite direction, that is, into the car. When turning to the 10 right the hand is moved outwardly as before, and the handle 23 swung on its pivot towards the left hand, as indicated by the dotted lines in Fig. 3, thus pulling back the rod 19 and swinging the hand upwardly to 15 an angle of 45 degrees, where it remains till the turn is made, after which it is drawn into the casing again by moving the handle back to its vertical position and drawing the rod 7 inwardly. In the same manner, when 20 slowing down or stopping, the hand is moved outwardly to the horizontal position and the handle pulled to the right hand, thus moving the rod 19 outwardly and swinging the hand downwardly to an angle of 45 degrees 25 where it remains until the stop is made or more momentum gained, after which it is drawn into and housed within the casing again.

It will be seen from the foregoing, therefore, that I have devised a simple, practical, and inexpensive signaling device for use on automobiles and other moving vehicles, whether of the open or closed type, and which is of great convenience and utility.

What I claim as my invention is:—

- 35 1. An automobile signaling device comprising, a casing open at one end and closed at its opposite end, a tubular rod extending horizontally through the closed end of the casing, a direction indicating device normally housed within the casing pivoted to the end of said rod whereby longitudinal movement of the latter projects the device horizontally from the casing, and a second 40 rod extending through the first mentioned one connected at one end to the said indicating device whereby longitudinal movement of the said second rod swings the projected device about its pivot.
- 45 2. An automobile signaling device comprising, a casing open at one end and closed at its opposite end, a tubular rod extending horizontally through the closed end of the casing, a direction indicating device normally housed within the casing pivoted to the end of said rod whereby longitudinal movement of the latter projects the device horizontally from the casing, a second rod 50 extending longitudinally through the first mentioned one connected at one end to the said indicating device whereby longitudinal movement of the said second rod swings the projected device about its pivot and a handle for operating said second rod pivotally mounted on the first mentioned one.

55 60 65 Dated at Nelson, B. C., this 29th day of January, 1925.

WILLIAM EDWARD FRANCIS GIBSON.
